UNITED STATES PATENT OFFICE.

WILLIAM A. CROSS, OF CHICAGO, ILLINOIS, ASSIGNOR OF ONE-HALF TO
THOMAS L. VESSEY, OF WASHINGTON, DISTRICT OF COLUMBIA.

TIE-FASTENER FOR PACKAGES.

SPECIFICATION forming part of Letters Patent No. 760,428, dated May 24, 1904.

Application filed December 22, 1902. Serial No. 136,295. (No model.)

To all whom it may concern:

Be it known that I, WILLIAM A. CROSS, a citizen of the United States of America, and a resident of Chicago, in the county of Cook and State of Illinois, have invented certain new and useful Improvements in Tie-Fasteners for Packages, of which the following is a specification.

The present invention relates to that class of ties or fasteners for holding the ends of a cord used in tying up packages of paper and the like, and has for its object to provide a simple, durable, and efficient tie-fastener in which convenience is afforded for drawing the cord tightly around the package and for firmly securing the free end of the cord in the tying operation in a rapid and easy manner, all as will hereinafter more fully appear and be more particularly pointed out in the claims.

In the accompanying drawings, illustrative of the present invention, Figure 1 is a perspective view of the present invention, illustrating the relative position of the parts during the tightening of the cord around the package just previous to securing the free end of such cord in the cord-gripping slot of the tie-plate; Fig. 2, a similar view illustrating the parts in a completely-fastened condition; Fig. 3, an enlarged detail elevation of the present tie or fastener plate.

Similar numerals of reference indicate like parts in the different views.

Referring to the drawings, 1 represents the cord or string by which the package or bundle is tied up.

2 is the tie or fastener plate of a flat and substantially rectangular form, the corners of which are preferably rounded, as shown in the drawings.

3 is an attaching-orifice formed in the plate 2, near one end of the same, for the passage and attachment of one end of the cord 1, by which the package is tied up.

4 represents counterpart recesses at opposite sides of the plate 2 and adjacent to the aforesaid orifice 3. Such recesses form a flat head at one end of the plate, around the undercut neck of which a loop at one end of the

fastener-cord 1 has engagement to afford a permanent and very substantial attachment 50 of such cord to the said plate.

5 is an open-sided orifice formed about the mid-length of the tie-plate 2, the entrance-passage to which is preferably formed by an oblique slot 6, extending from the orifice 5 to 55 one side of the tie-plate.

7 is a tapering gripping-slot formed longitudinally in the end of the tie-plate opposite to the attaching-orifice 3 and in which the free end of the attaching-cord 1 is forcibly 60 drawn by hand, so as to be firmly held in the final fastening of the cord around a package or bundle.

In a practical use of the present invention the cord 1, carrying at one end the tie-plate 2, is looped around the package in the manner shown or in any other usual and suitable manner, after which the loose end of the cord is placed in the open-sided orifice 5, the tie-plate being turned on its edge, as shown in Fig. 1, 70 to facilitate such insertion. By pulling upon the free end of the cord, with the margin of the orifice 5 forming a bearing, the operator is enabled to tighten the cord around the package to any required extent, after which the 75 free end of the cord is forcibly drawn into the tapering gripping-slot 7 and the tie-plate turned flatwise upon the package to complete the fastening operation.

With the present improved construction the 80 open-sided orifice 5 affords a ready means whereby a series of the tie-fasteners, with their attached cords, can be hung upon a supporting-wire for ready and convenient access and use.

Having thus fully described my said invention, what I claim as new, and desire to secure by Letters Patent, is—

1. A tie - fastener, comprising an oblong plate member, having a cord-attaching orifice 90 at one end, a longitudinal wedge-shaped engaging recess at the other end, and an oblique bearing - recess arranged intermediate the length of the plate and opening through one side of the same, for the purpose set forth. 95

2. A tie - fastener, comprising an oblong

plate member, having a flat head at one end and a cord-attaching orifice in said head, a longitudinal wedge-shaped recess at the other end, and an oblique bearing-recess arranged 5 intermediate the length of the plate and opening through one side of the same, for the purpose set forth.

Signed at Chicago, Illinois, this 22d day of November, 1902.

WILLIAM A. CROSS.
